UNITED STATES PATENT OFFICE.

JAY WILCOX, OF GRAND RAPIDS, MICHIGAN.

TREE-SPRAYER.

1,252,756.

Specification of Letters Patent.

Patented Jan. 8, 1918.

Application filed July 6, 1915. Serial No. 38,356.

To all whom it may concern:

Be it known that I, JAY WILCOX, a citizen of the United States, residing at Grand Rapids, in the county of Kent and State of Michigan, have invented certain new and useful Improvements in Tree-Sprayers, of which the following is a specification.

My invention relates to improvements in the governing elements in a fruit spraying machine, and its object is to provide a means whereby the spraying pumps may be made inoperative as soon as an excess of pressure is created in the conductor pipes by the direct action of said pumps automatically cutting off the flow of the spraying solution before it reaches the pumps, thus dispensing with the ordinary overflow and waste beyond the pumps.

I attain this object by the mechanism illustrated in the accompanying drawing, in which Figure 1 is an elevation of the diaphragm chamber and its several connections for carrying out the object of this invention: Fig. 2 is a side elevation of the same: Fig. 3 is a top plan of the same showing the relative positions of its several elements: Fig. 4 is a longitudinal section of a part of the pipes and valves in the system, upon a large scale to show the operation of my mechanism for cutting off the flow of spraying solution before it reaches the pump.

Similar numerals refer to similar parts throughout the several views.

In the accompanying drawing 1 represents the supply pipe through which the spraying solution is drawn from the tank 21, indicated in Fig. 1. 3, 3 represent check valves between the pumps 4, 4 and the intake pipe 1, and 3', 3' represent check valves between the pumps 4, 4 and the pipe 13 that conveys the solution into the chamber 5, as indicated at 13', which chamber is provided with a flexible diaphragm 5', arranged to actuate the rod 6 in the usual manner. To carry out the objects of my invention I secure a yoke 7 to the upper end of the rod 6, which is provided with arms that extend downward and are made to engage the rods 10, as indicated at 8, 8 in Figs. 1, 2 and 3. I place a nut, 11, at the upper end of each of the rods 10 and a spiral spring 9 between each of these nuts and the corresponding end 8 of the yoke 7; the nuts 11 being designed to enable me

to adjust the pressure of both the springs 9, 9 to exactly the same tension. The lower ends of the rods 10, 10 are securely packed upon the flexible packing 19 by means of properly formed and applied nuts 12. This flexible packing is made of rubber, or any other firm, reliable material that will deflect sufficiently to allow the rods to raise and lower with the yoke 7 and the rod 6 as they are affected by varying pressure in the chamber 5. The rods 10 pass below the flexible packing 19 and are pivotally connected with the levers 17, as at 15. One end of the levers 17 is pivotally secured in the pipe 20 to one side of the rods 10, and the other ends 60 are free to raise and lower under the valve 18, as indicated in Fig. 4. Normally the lever 17 is in position to allow the valve ball 18 to seat perfectly on its seat 18' so no solution that has been drawn up past the valve 18 by the pumps, can flow or be forced back past the valve, but when over-pressure is forced into the chamber 5 the diaphragm will be forced upward, in the usual manner and will carry the yoke 7 upward, as indicated by its dotted lines in Fig. 1, which will raise the rods 10, 10 causing the flexible packing to bend upward as indicated by its dotted lines in Fig. 4, so 65 the lever 17 will be raised upward and will carry the valve 18 upward with it upon the up-stroke of the pump, and will hold the valve open so any solution that is drawn from the tank by the pumps upon their up-stroke will be forced back past the 70 valve on the downward strokes of the pumps and prevent any solution from passing through the pumps until the pressure has been reduced to the desired degree when 75 the diaphragm ceases to act upon the rod 17, will allow the lever 17 to drop down to 80 normal position and the pumps to operate in the usual manner until the pressure has 85 again become excessive in the diaphragm 85 chamber.

In practice the solution is drawn from the tank 21 through the pipe 1, the pipes 20, and the valves 3-18 into the pump 5, and thence is forced through the pipes 20' the valves 3' 90 and the pipe 13 into the chamber 5 and through the pipe 14 to the proper air chambers and spraying nozzles in the usual manner; the air chambers and spraying nozzle have not been shown in the drawings for the 95 reason that neither of them enter, in any 100 105 110

way, into the invention herein disclosed and claimed, as the entire invention is fully disclosed in Fig. 4.

It will be readily understood that the 5 lines of pipes, including connections, elbows &c. from the intake pipe 1 to the pump 4, and 20' represent the like line of pipes from the pumps 4 to the pipe 13 that leads to the diaphragm chamber 5, and that no pressure 10 is produced at any time in the pipe between the intake pipe 1 and the check valves 18 in the chambers 3, hence the moment excessive pressure is produced in the chamber 5 and the pump piston, on the upward stroke, 15 raises the valve 18 for the passage of the spraying solution the lever 17, pivoted at 16 and 15, will be so actuated by the diaphragm that the end immediately under the valve 18 will hold the valve passage at 18' 20 open for the free passage of the solution in either direction until the pressure in the chamber 5 is reduced to the desired degree.

As the diaphragm used in this connection is exactly similar to all diaphragm used in 25 this class of sprayers, and its action is perfectly understood by those versed in this particular art, I have not deemed it necessary to enter particularly into a description of this feature, especially as it forms no part of my 30 invention. For the same reason I have refrained from entering into a detailed description of the pumps or any other feature that, though essential to the successful working of the system as a whole, are not 35 included in my present invention.

The edge of the flexible packing 19 must be so firmly secured between the ring 19' and the shoulder on the barrel 2 as to form a perfectly safe, air and water tight joint, and 40 the center connection with the rod 10 must be of the same nature and the packing must be made of some flexible material that will not be affected by the action of the spraying solution. The reason I prefer this form of 45 packing is that its movements will be perfectly free thus rendering the adjustment of the rod 10 free and easy, while with an ordinary packing box the friction on the rod, necessary to insure a water tight joint would 50 be so great as to greatly hamper the movement of the rod, and, in fact, to render it almost impossible to properly operate the lever for actuating the valve 18, as desired.

It will be understood that the desired action, in this instance, is brought about by 55

the direct action of the spraying pumps in the conveyer pipes without the use of additional machinery, or pressure producing elements, and without the entrance of air into any part of the conductor pipes or their attachments.

What I claim as new, and desire to secure by Letters Patent of the United States, is:—

1. In combination with the intake pipe, 65 conductor pipe, pumps, check-valves and a diaphragm of a tree spraying machine, a lever inside of the conductor pipe below the diaphragm, one end of said lever pivotally connected inside of the conductor pipe, near 70 the intake pipe, the free end of the lever resting against the under surface of the valve, and a rod suspended from the diaphragm and connecting the center of the diaphragm with the lever between its pivotal connection and the check valve to raise 75 and lower said valve by direct pressure from the spraying pumps inside of the conductor pipe.

2. In combination with the intake pipe, 80 pumps, conductor pipe, check valves and diaphragm of a tree spraying system, levers pivotally connected at one end to the inside of the conductor pipes with the free ends of the levers in position to actuate the check 85 valves, a rod connected with the diaphragm and carrying a yoke outside of the conductor pipes, rods extending from the ends of the yoke, passed through proper bearings in the conductor pipes and connected with the levers to unseat the valves by the direct pressure of the pumps inside of the conductor 90 pipes.

3. In combination with the intake pipes, 95 check valves, conductor pipes, force pumps and diaphragm of a tree sprinkler system, levers pivotally mounted at one end in the conductor pipes, the free ends of the levers in contact with the check valves, a rod connected with the diaphragm and carrying a 100 yoke outside of the conductor pipes, adjustable rods connected with the yoke, passing into the conductor pipes and connected with the levers to unseat the check valves by the direct pressure inside of the conductor pipes, 105 and flexible packing connected therewith.

Signed at Grand Rapids, Michigan, July 2, 1915.

JAY WILCOX.
